UNITED STATES PATENT OFFICE.

HENRY FAIRBANKS AND FREDERICK W. TAYLOR, OF ST. JOHNSBURY,
VERMONT, ASSIGNORS TO THE E. & T. FAIRBANKS & COMPANY, OF
SAME PLACE.

PRINTING-REGISTER FOR WEIGHING-SCALES.

SPECIFICATION forming part of Letters Patent No. 616,303, dated December 20, 1898.

Application filed April 4, 1898. Serial No. 676,418. (No model.)

To all whom it may concern:

Be it known that we, HENRY FAIRBANKS and FREDERICK W. TAYLOR, citizens of the United States, residing at St. Johnsbury, in the county 5 of Caledonia and State of Vermont, have invented certain new and useful Improvements in Printing-Registers for Weighing-Scales, of which the following is a description, reference being had to the accompanying drawings and 10 to the letters of reference marked thereon.

Our invention relates to an improvement in printing-registers for weighing-scales, of which a type is shown in the patent granted Henry Fairbanks, No. 597,640; and the object 15 of the present invention is to provide certain advantageous details in the construction of the poise, poise-slides, &c.

The invention consists in the matters hereinafter described and referred to in the appended claims.

In the accompanying drawings, which illustrate the invention, Figure 1 is a side elevation, partly in section, of a portion of a printing-beam embodying our invention. Fig. 2 is a section taken at B, Fig. 1. Fig. 3 is a section taken at A, Fig. 1; and Fig. 4 is a section taken at C, Fig. 1.

In the drawings the main poise, which by means of rollers *c* is guided on the main beam *b*, is constructed as shown in the sectional views, preferably with an inclined front wall, as shown at *x*. The main poise is manipulated by the latch *d* in the ordinary way.

Projecting inwardly from the wall *x* of the main poise are integral projections *z*, which are provided with a squared groove, in which is guided the rib *y*, screwed to the upper edge of the first poise-slide *e*. This rib *y* is preferably of a strip of steel and throughout a portion of its length is provided with notches *u* to receive the roller upon the end of the spring-arm *s*, which is secured to the upper edge of one of the projecting pieces *z*. One of these 45 projecting pieces *z* is preferably arranged in a plane directly above the platen, and it fits

closely over the slide, as shown in Figs. 2 and 4, and forms a backing against the stress of the printing pressure. So, also, by providing the guiding-strip *y* with notches the downward pressure of the roller on the spring-arm *s* is practically brought over the supporting rollers *q*, upon which the poise-slides have an antifriction bearing. The second poise-slide *f* has throughout a portion of its length 55 an inwardly-projecting part, as shown in Fig. 2, which backs up against the first poise-slide *e*, and this second poise-slide *f* has also a notched piece *u*, upon which bears the roller on the end of the spring-arm *s'*, also secured 60 to one of the projecting pieces *z*. The poise-slide *e* is moved through the medium of the thumb and finger piece *h* and the pinion *g*, engaging teeth on the under side of said poise-slide, while the second poise-slide *f* is similarly moved by the thumb and finger piece *h'* and the pinion *g'*. The poise-slides *e* and *f* are grooved on their under sides to snugly fit their supporting-rollers *q* *q'*.

Having thus described our invention, what 70 we claim as new, and desire to secure by Letters Patent, is—

1. In combination with the main beam, a poise slideable thereon, an inwardly-projecting part on said poise, a poise-slide having 75 means for engagement and guidance on the said projection, and means for operating said poise-slide; substantially as described.

2. In combination with the main beam, a poise slideable thereon having inwardly-extending projections, a guideway formed in said projections, and a poise-slide having a projection in engagement with said guideway; substantially as described.

3. In combination with the main beam, a 85 poise slideable thereon having inwardly-extending projections formed with a groove, and a poise-slide provided with a rib engaging said groove; substantially as described.

4. In combination with the main beam, a 90 poise slideable thereon having inwardly-extending projections formed with a groove,

and a poise-slide provided with a rib engaging said groove, said rib being also provided with notches, and a spring-roller supported from one of said projections engaging said 5 notches; substantially as described.

5. In combination with the main beam, a poise slidable thereon having inwardly-extending projections formed with a groove, and a poise-slide provided with a rib engaging said groove, one of said projections being 10

attached to the main poise directly above the printing-platen.

In testimony whereof we affix our signatures in presence of two witnesses.

HENRY FAIRBANKS.
FREDERICK W. TAYLOR.
